UNITED STATES PATENT OFFICE

HAROLD G. VAUGHN, OF WARREN, OHIO, ASSIGNOR TO THE OHIO CORRUGATING COMPANY, A CORPORATION OF OHIO

MACHINE FOR EXPANDING CYLINDERS

Application filed July 1, 1927. Serial No. 202,916.

This invention relates to the art of expanding cylindrical sheet metal bodies, such as steel barrels, drums, and other shipping containers, and comprises a new and useful means 5 for producing annular corrugations or ribs in the cylindrical wall of such containers to strengthen the same and to facilitate rolling movements thereof. The object of the invention in general is to provide a machine which 10 will produce a plural number of such circumferential ribs of substantial size in separate zones simultaneously, or in other words, concurrently in a single expanding operation. The machine is therefore constructed with 15 separate sets of dies adapted to move outwardly on radial lines from a common axis to expand the cylinder uniformly in two places, and at least one set of dies is adapted to move longitudinally of the axis in that operation, to permit the stock to draw or flow 20 lengthwise of the cylinder. Thus as the cylinder is stretched or expanded circumferentially by the dies in two separated places or zones the stock flows freely from the opposite ends 25 of the cylinder toward each zone or area of expansion, and drawing of the stock at the middle of the cylinder is also effectively permitted, all without impedance or hindrance from the dies and without causing the middle 30 or expanded portions of the cylinder to be weakened or ruptured.

In the accompanying drawings, Fig. 1 is a side elevation of the machine, and a sectional view of a plain cylinder sleeved over 35 the dies, and Fig. 2 is a similar view with the dies and cylinder expanded. Figs. 3 and 4 are side elevations of a plain cylinder and a corrugated cylinder. Fig. 5 is a horizontal section of the machine on line 5—5 of Fig. 40. Figs. 6 and 7 are corresponding sectional views of the machine in a vertical plane, showing the dies contracted and expanded as in Figs. 1 and 2, respectively. Fig. 8 is a top view of the machine. Figs. 9 to 12 are 45 detail elevations and sections on a larger scale of one of the upper die segments and the lift springs therefor as used in the machine.

The machine comprises a frame 2 upon 50 which a motor 3 is mounted in driving connection with gearing 4 suitably arranged to

rotate a crank or cam shaft 5 at a slow speed, say one revolution for each cylinder expanding operation. An eccentric strap 6 connects the crank, cam or eccentric portion of shaft 5 with the lower end of a reciprocable shaft 55 or thrust rod 8 which extends through and is supported vertically within a bearing 9 in a bed or base plate 10 at the top of frame 2. In practice the base part of the machine is placed in a pit with base plate 10 on a level 60 with the floor of the work shop. The remaining working parts of the machine are projected above the floor and comprise in part a relatively long sleeve 11 on rod 8 and a flanged nut 12 in screw-connection with the 65 upper screw-threaded end of rod 8. Tie rods 14, coiled springs 15, and nuts 16 secure sleeve 11 in suspensory connection with flanged nut 12, and a lock nut 17 serves to fix flanged nut 12 in rigid connection with rod 8 following 70 vertical adjustment of sleeve 11 on said rod. Separate sets of toggle links 18 are pivotally secured to channeled pieces 19 screwed lengthwise to the flat sides or faces of sleeve 11, and the outer ends of the toggle links of 75 each set are pivotally connected to a series of individually movable die-carrier members 20 arranged radially in respect to thrust rod 8 and forming segmental parts of a complete circle. Members 20 embody ribbed feet or 80 supporting extensions 22 adapted to slide in and upon the radially channeled top of bed plate 10 and these members are secured for 85 slideable movement on the base plate by means of a top bearing ring 23 and tie rods 24, see Fig. 6. The die-carrying members and the other structural details so far described are in general substantially the same as in the machine shown and described in Letters Patent of the United States No. 1,524,106, 90 granted to C. H. Riegel, January 27, 1925. However and beginning at this point the present machine differs from the known machine in that each of the die-carrying members 20 supports a pair of dies or die-sections; a fixed die section 25 and a relatively movable die-section 26, the latter being spaced apart 95 and mounted to move toward the first die-section. As shown, each movable die-section 26 is formed with a rabbeted slot 27 extend- 100

ing lengthwise thereof, and a flanged piece 28 is fastened by screws 29 within the slot to hold the die section slidably upon carrier member 20, see Figs. 10 and 11. The slot is longer than holding piece 28 to permit die section 26 to slide only a limited distance lengthwise of carrying member 20, and the upper end of die section 26 is flanged inwardly and rests upon a pair of coiled compression springs 30 seated within sockets at the top of member 20. Die sections 26 are upheld in movable spring yielding position relatively to the fixed set of die sections 25, as delineated in Figs. 1 and 6, and both sets of die sections are ribbed to permit annular beads or corrugations to be produced in a plain cylinder A when all such sections are simultaneously expanded. Thus the fixed die sections have outwardly-extending ribs 31 arranged in a circle a predetermined distance above the ribbed feet 22 of carrier members 20, and the longitudinally slidable die sections 26 having similar bead forming ribs or projections 31' annularly thereof at or near their lower ends. The spacing of the ribs 31 and 31' may be varied, but as shown these ribs are spaced substantially equidistant from each other and the opposite ends of a plain cylinder A after it has been sleeved over said dies and placed upright upon the ribbed feet 22, say as shown in Fig. 1.

When cylinder A is in place as stated the dies are contracted, that is drawn inwardly as shown in Figs. 5 and 6. Starting of the machine will revolve the eccentric shaft and in the first half revolution thereof draw rod 8 and sleeve 11 downwardly, thereby straightening the toggle links 18 and forcing all of the die-carrying members 20 outwardly in unison. As the dies move outwardly the bead-forming ribs 31 and 31' engage the inner wall of cylinder A and expand the same circumferentially. Such expansion of the sheet metal simultaneously at the two separated places draws the outer ends *a—a* of the cylinder toward the ribs, and the middle belt or area *a'* of the cylinder is also effected, that is, it becomes narrower. Such narrowing of the cylinder belt is possible because the slidable dies 26 are free to move with the stock toward the fixed dies 25 and the necessary stock for forming relatively deep annular beads or corrugations *b—b* is also thereby provided without stretching or rupturing the middle area or belt *a'* of the cylinder. Obviously, both sets of dies might be made to slide relatively to each other, but a single set has been found to function satisfactorily where only two beads or corrugations are being expanded simultaneously in a plain cylinder.

The expanding operation is completed in one-half revolution of the eccentric or crank shaft, and the remaining part of the revolution

restores the working parts to the same position as at the beginning with the ribbed cylinder released and free to be removed from the contracted dies.

What I claim, is:

1. A machine for expanding cylinders, comprising radially shiftable rigid means adapted to expand a sheet metal cylinder circumferentially, said means being arranged to move longitudinally in respect to the axis of the cylinder coincidently with the longitudinal draw movement of the material as it is being expanded. 70

2. A machine for expanding cylinders, comprising coacting and radially shiftable rigid devices adapted to expand a sheet metal cylinder circumferentially at spaced places therein, said devices being arranged to move longitudinally in respect to the axis of the cylinder coincidently with the longitudinal flow of the material in the area between the places being expanded. 80

3. A machine for expanding cylinders, comprising radially shiftable expanding means adapted to bead a sheet metal cylinder circumferentially at two places simultaneously, including rigid dies movable radially and longitudinally in respect to the axis of the cylinder. 90

4. A machine for expanding cylinders, comprising separate sets of radially shiftable rigid dies adapted to expand a cylinder circumferentially in different zones thereof, and at least one set of said dies being adapted to move longitudinally of the axis of said cylinder in expanding operations to permit the stock to flow lengthwise of the cylinder. 95

5. A machine for expanding cylinders, comprising a set of radially shiftable rigid dies adapted to expand a circumferential bead in a cylinder, and a second set of radially-shiftable dies adapted to shift longitudinally in respect to the first set of dies to expand a second circumferential bead in the same cylinder concurrently with the production of the first bead. 105

6. A machine for expanding cylinders, comprising a set of radially-arranged and radially shiftable rigid dies adapted to produce a circumferential corrugation in a sheet metal cylinder, and a second set of radially expanding dies yieldingly supported for movement lengthwise of the cylinder adapted to produce a second circumferential corrugation in the same cylinder. 115

7. A machine for expanding cylinders, comprising a series of radially-arranged members, and separate sets of rigid corrugating dies secured in spaced relation to said members; one set of dies being arranged to move toward the other set of dies during corrugating operations. 125

8. A machine for expanding cylinders, comprising radially arranged members having toggle-link activating connections, sep- 130

arate sets of corrugating dies mounted upon said members, one set of dies being spring pressed and adapted to slide toward the other set of dies during corrugating operations.

9. A machine for expanding cylinders, comprising radially arranged members having separate sets of beading dies mounted thereon, one set of dies being supported by springs in slidable position upon said members, and toggle links and reciprocable means adapted to move said members and dies on radial lines.

10. A machine for expanding cylinders, comprising radially-movable members, a set of dies fixed to said members having corrugating ribs, a second set of dies slidably mounted upon said members having corrugating ribs, and means adapted to hold said separate sets of dies normally separated.

In testimony whereof I affix my signature.
HAROLD G. VAUGHN.
